UNITED STATES PATENT OFFICE.

FRANK WM. RICHEY AND SUMNER M. ROBBINS, OF RATON, TERRITORY OF NEW MEXICO.

SEAL-LOCK.

SPECIFICATION forming part of Letters Patent No. 369,884, dated September 13, 1887.

Application filed May 26, 1887. Serial No. 239,423. (Model.)

To all whom it may concern:

Be it known that we, FRANK WILLIAM RICHEY and SUMNER M. ROBBINS, of Raton, in the county of Colfax and Territory of New Mexico, have invented a new and Improved 5 Seal-Lock, of which the following is a full, clear, and exact description.

This invention relates to seal-locks for freight-car doors, the object of the invention being to 10 provide a simple, cheap, and durable seal-lock and one which may be operated without the use of pinchers or pliers; and to this end the invention consists of a lock and bolt adapted to receive a sealing-strip, as will be hereinafter 15 more fully described, and specifically pointed out in the claims.

Reference is to be had to the accompanying drawings, forming a part of this specification, in which similar figures of reference indicate 20 corresponding parts in all the views.

Figure 1 is a side view of a car-door and a portion of a car-body, representing the same as being provided with our improved form of seal-lock. Fig. 2 is a cross sectional view 25 taken on line *xx* of Fig. 1. Fig. 3 is a sectional plan view taken on line *yy* of Fig. 1. Fig. 4 is a view of the sealing-strip prior to its use, and Fig. 5 is a view of the strip as it appears after having been used in the lock.

30 In the drawings above referred to, 10 represents the car-door, which may be hung in any of the well-known ways. To this door there is connected a hasp, 11, the end of which is apertured, as shown at 12, to receive a staple, 13, that is driven in and secured to the door-post. Beneath this staple I mount a lock case, 14, that is arranged to receive a locking-bolt, 15, and also to receive a sealing-strip, 16, which is inserted through apertures 2, that are formed 35 in the side walls of the lock-case. That end of the bolt 15 which enters the case 14 is provided with a spring-tongue, 17, the extreme end of which is bent outward, while the extreme end of the bolt proper is cut away, as 40 shown at 3. Just beyond this cut-away portion 3 there is formed a shoulder, 4, so that there is a space between the tongue 17 and the bolt, and in this space, as will be hereinafter explained, the sealing-strip 16 rests. The 45 spring-tongue 17 is formed with an aperture, 50

5, beneath which there is a registering aperture, 6, formed in the bolt 15.

A plunger, 18, that is formed with a punch-point, 19, is mounted in a housing, 20, which extends outward from the lock-case 14, the plunger being normally held in the position in which it is shown in Fig. 3 by the action of a spring, 21, which is coiled about the plunger-stem and abuts against a flange, 22, that is formed between the punch-point 19 and the 60 stem of the plunger. The seals which are shown in Fig. 4 consist of strips of metal on which there are formed projections 7.

In practice, when it is desired to seal a lock, the hasp 11 is brought into engagement with 65 the staple 13, and the bolt 15 is passed through the staple and into the lock-case 14, one of the sealing-strips having been previously inserted within the apertures 2 of the lock-case, the sealing-strip being so adjusted 70 that its bosses or projections 7 will be upon either side of the bolt cavity. Then as the bolt is forced inward, the plunger at this time being drawn back against the tension of the spring, the sealing-strip will be borne upon 75 by either the outturned edge of the spring-tongue 17 or by the cut-away face 3 of the bolt, and as the bolt is forced home the sealing-strip will enter the space above the shoulder 4. After the parts have been adjusted as 80 described, the point of the plunger is permitted to enter the slot in the spring-tongue 17. The lock is now sealed, for the sealing-strip cannot be drawn out of the lock-case, owing to the formation of its projections 7, said projections being of sufficient size to prevent the drawing of the strip between the bolt end and the tongue formed thereby, nor can the bolt be withdrawn, as its shoulder 4 will strike against the sealing-strip; but when the car has reached its 85 destination and it is desired to open the door a slight tap upon the extending end of the plunger will force the point 19 inward and the sealing-strip will be severed, as is represented in Fig. 5, after which the ends of the severed 90 strip may be removed from the lock-case and the bolt withdrawn.

Now, although we have illustrated this seal-lock as arranged in connection with a hasp-fastener, it will of course be understood that 95

any other form of fastening employing a bolt might be used in connection with a lock.

Having thus fully described our invention, we claim as new and desire to secure by Letters Patent—

1. The combination, with an apertured bolt provided with an apertured spring-tongue and formed with a shoulder near its forward end, of a lock-case adapted to receive the bolt and formed with transverse openings, and a plunger carried by the lock-case and adapted to enter the apertures of the spring-tongue and bolt, substantially as described.

2. The combination, with a bolt formed with a cut-away portion, 3, a shoulder, 4, and an aperture, 6, of a spring-tongue, 17, formed with an outturned end, a bolt or lock case, 14,

formed with transverse apertures, a sealing-strip, 16, formed with projections 7, and a means, substantially as described, for breaking the strip, as and for the purpose stated.

3. The combination, with a bolt formed with a cut-away end, 3, a shoulder, 4, and an aperture, 6, of a spring-tongue, 17, formed with an aperture, 5, and an outturned end, a bolt or lock case formed with apertures 2, a plunger, 18, a spring, 21, arranged in connection with the plunger, and a sealing-strip, 16, formed with projections 7, substantially as described.
